UNITED STATES PATENT OFFICE.

J FRANK ALLARD, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed June 8, 1921. Serial No. 476,067.

To all whom it may concern:

Be it known that I, J FRANK ALLARD, a citizen of the United States, residing in Brooklyn borough, in the county of Kings, city and State of New York, have invented certain new and useful Improvements in Typewriting Machines, of which the following is a specification.

This invention relates to typewriting machines of the class shown in the Wernery & Snaith Patent, No. 1,132,055, in which a longitudinally folded web is led around the revoluble platen of a typewriting machine, the latter having provision for carrying carbons between the plies of the web and for shifting the carbons back to face fresh portions of the web as the typing proceeds; the web usually comprising a succession of printed forms, each of which is torn off as soon as typed.

The present invention contemplates the use of separate plies instead of a folded web. These plies are each carried upon a spool mounted below and at the rear of the carriage, and difficulty is experienced in drawing the plies from the spools in the operation of line-feeding the plies around the platen. It is one feature of this invention to provide improved means whereby the plies may be withdrawn from the spools for a distance somewhat in excess of the length of one form or bill before the typing of a form is begun, the portions of the plies thus withdrawn hanging from the spools in loops which are used up in the process of typing a form.

A further feature of this invention is the provision of separately mounted clamps on the carbon-paper carriage, one at each side thereof, said clamps being independent of each other and each having means tending to hold the respective clamp in effective position to grip the work-sheets at the rear of the carbon-paper carriage. During the return of the carbon-paper carriage, when the carbon-sheets are moved rearwardly to face fresh portions of the plies of work-sheets, it is necessary for the clamps to be in ineffective or non-gripping position, so that the clamps may move rearwardly with the carbon-paper carriage to fresh portions of the work-sheets. For this purpose, means is provided for simultaneously operating both clamps to release them. When the carbon-paper carriage has been returned, and it is

necessary to grip the work-sheets, the releasing means is removed, and each clamp is restored to gripping or effective position by the means which hold them normally in such position.

If the clamps were interconnected instead of independent, both would swing toward gripping position when the releasing means was removed, and if one clamp contacted with the sheets sooner than the other, the latter would not be able to grip the sheets firmly. In the present invention, each clamp moves to effective position independently, and each is operated by separate means for swinging the respective clamp to gripping position.

By clamping the work-sheets, as described above, they prevent accumulation of relative creeping between the plies of work-sheets, as they feed around the platen, due to the greater linear distance which the outer work-sheet travels. The clamps prevent the creeping which has taken place during the typing of a set of forms from being transmitted to the forms back of the clamps, and thus prevent an accumulation of such creeping. After a set of forms has been typed, the platen is elevated, and the plies are straightened out and torn off. Any creeping which has taken place in the typed forms is eliminated, so far as the remaining forms are concerned, when the typed forms are torn off, since the clamps effectually prevent the relative shifting of the portions of the plies to the rear thereof.

Other features and advantages will hereinafter appear.

In the accompanying drawings,

Figure 1 is a fragmentary perspective view of an Underwood continuous billing typewriter carriage, showing the present invention applied thereto.

Figure 2 is a side view, vertically sectioned, of the carbon-paper carriage and a clamp mounted thereon, the clamp being in lowered or effective position to grip the plies of work-sheets.

Figure 3 is a view similar to Figure 2, but showing the clamp in raised or ineffective position.

Figure 4 is a plan view of the carbon-paper carriage and the clamps applied thereto.

Figure 5 is a view, showing the carbon-paper carriage advanced on the carriage ex-

tension to withdraw portions of the plies of work-sheets from their respective spools.

Figure 6 is a view similar to Figure 5, but showing the carbon-paper carriage in rearward position, the portions of the plies unwound from the spools hanging in loops from their respective spools.

In the Underwood continuous billing machine of the type referred to, a carriage comprises a platen 10, around which plies of work-sheets 11, 12, 13 and 14 and interleaved carbon-sheets 15, 16 and 17 are fed, said platen being swingable upwardly from the Figure 1 position to permit the plies to be straightened out, as fully set forth in the patent to Wernery & Smith, cited herein. The carriage is provided with a rearward extension 20 comprising side rails 21, upon which is mounted by rolls (not shown) a forwardly and rearwardly-reciprocating carbon-paper carriage 22 having stepped side pieces 23, upon which steps are mounted from alternate sides, carbon-sheet clamping bars 24 for clamping the rear ends of the carbon-sheets, plies of work-sheets passing from the rear and interleaving with the carbon-sheets. The carbon-paper carriage 22 has fixed thereto a forwardly-extending handle 25 for returning the carbon-paper carriage to the rear to face fresh portions of the work-sheets.

The layers of work-sheets and carbon-sheets are fed forwardly around the platen in the operation of typing a form on the work-sheets. The plies of work-sheets are usually supplied from large and heavy spools mounted at the rear and below the carriage, and the burden of unwinding all of the spools is carried by the line-space lever at each line-space operation. This causes the platen to slip relatively to the web, and it is, therefore, desirable to withdraw a sufficient portion of the plies from the spools before the typing of a form is begun, so that no further withdrawals from the spools need be made until the form is fully typed. After the typing of a form has been completed, the carbon-paper carriage is returned to the rear by means of handle 25 and the typed forms may then be severed. The parts are then in the Figure 1 position ready for the typing of the next form. Before such typing is begun, however, means is provided on the carbon-paper carriage for clamping or gripping the work-sheets and for moving the carbon-paper carriage forwardly a distance equal to or slightly greater than the length of a form to unwind the spools upon which the plies are wound. The carbon-paper carriage is then again moved rearwardly, the unwound portions of the plies hanging in loops from the spools, thus offering little resistance to the forward movement of the carbon-paper carriage in the line-space operation. For

thus clamping the work-sheets, there is provided at each side of the carbon-paper carriage a fixed jaw 30 in the form of a flat plate 31 attached to the base of the carbon-paper carriage, the jaw 30 extending to the rear of the carbon-paper carriage and inwardly for a short distance. Co-operating with each fixed jaw 30 is a swinging jaw 32 at the rearward end of an arm 33, which is pivotally mounted at its forward end at 34 on a portion 35, which may be struck up from the plate 31, said jaw 32 extending inwardly a distance substantially the same as jaw 30 and lodging in a depression 36 in the latter. Each set of jaws is normally held in gripping or effective position by a spring 40 fixed to the plate 31 and to arm 33, so that any sheet passing between the jaws will be firmly gripped. To prevent upward movement of jaws 32 against the action of their springs 40, there are provided locking pins 41 operating in cam-slots 42 formed in the arms 33, said pins being operated in said slots by arms 44, to which they are fixed, said arms 44 being fixed to a rock-shaft 45 journaled in standards 46, which may be struck up from plate 31. For rotating the rock-shaft, there is provided a forwardly-extending link 49 terminating in a handle 50 adjacent the forward end of handle 25, so that the thumb and forefinger can grasp the ends of both handles, the handle 50 operating a rock-arm 51 fixed to the end of shaft 45. The handle 50 is provided with a slot 53, to embrace a guide-pin 52 fixed to handle 25, the link 49 being normally held rearwardly by a spring 54 fixed to handle 25 and link 49, to hold arm 51 and arms 44 rearwardly, and, hence, maintain pins 41 at the rear of cam-slots 42 to lock jaws 32 against upward movement.

The jaws 30 and 32 of the clamps being thus held in gripping relation and the parts being as shown in Figure 1, the carbon-paper carriage is drawn forwardly a distance equal to or exceeding the length of one form, as in Figure 5, and is then returned to the Figure 1 position, the portions of the plies withdrawn from the spools hanging in loops, as shown in Figure 6. The typing may now proceed as usual without excessive burden being placed on the line-space handle in the operation of line-spacing the platen. When a set of forms has been fully typed and the carbon-paper carriage is to be returned to the rear, means must be provided for releasing the clamps which holds the plies, so that the carbon-paper carriage may be free to return, and so that the clamps may be moved rearwardly to grip a fresh portion of the plies. The clamps are released by swinging arms 33, and hence jaws 32, upwardly, and for this purpose, the end of handle 50 is pulled toward the end of handle 25 against the action of spring 54, the slot 120

53 moving forwardly until the pin 52 contacts with the rearward end thereof, and arm 51 being rotated forwardly to rotate arms 44 and pins 41 forwardly, the latter 5 contacting with the under surfaces of arms 33 to raise said arms and jaws 32 to ineffective or non-gripping position, as in Figure 3. The carbon-paper carriage is returned to its rearward position and the handle 50 is 10 released, thus swinging pins 41 rearwardly and permitting springs 40 to snap the respective jaws 32 independently into contact with jaws 30 to grip the plies one form length to the rear of the former gripping 15 point. The spring 54 draws the handle 50, arm 51, arms 44 and pins 41 rearwardly, said pins riding to the ends of cam-slots 42 to hold jaws 32 in the lowered or gripping position. The carbon-paper carriage may then 20 be drawn forwardly to unwind the spools preparatory to typing a set of forms, as hereinbefore described.

It will thus be seen that gripping of the work-sheets by the co-operating jaws 30 25 and 32 is insured in the effective position of the clamps, since each jaw 32 operates independently and is normally pulled downwardly by its respective spring 40. If the jaws 32 were interconnected, and one of 30 them pressed against its jaw 30 sooner than the other, the latter would not firmly grip the sheets below it. This objection is avoided by mounting the jaws 32 at each 35 side independently of the other and by providing separate means for drawing each downwardly to effective position. It will further be seen that by mounting the clamps to the rear of the carbon-paper carriage, they can remain in gripping or effective 40 position while fresh carbon-sheets are being attached to the clamping bars, whereas if the clamps were mounted at the front of the carbon-paper carriage they would have to be released before access could be had 45 to the clamping bars. It will be further observed that any creep which takes place in the set of forms being typed, due to the greater linear distance which the outside sheets around the platen must travel, will 50 not be transmitted to the forms back of the clamps, or, in other words, the creeping will not be permitted to accumulate. As soon as a set of forms has been typed and the platen is raised to straighten the webs, the 55 forms of the typed set will straighten themselves out, and when cut off, the creep which arose in typing will not affect the remaining portion of the plies which have been held by the clamps against shifting. Still 60 another advantage to be noted is the mounting of the clamps at the rear of the carbon-paper carriage out of contact with the carbon-sheets, so that when jaws 32 are snapped into contact with jaws 30, no carbon impression is produced on the work-sheets, as 65

would be the case if the clamps were mounted at the front of the carbon-paper carriage.

Variations may be resorted to within the scope of the invention, and portions of the 70 improvements may be used without others.

Having thus described my invention, I claim:

1. In a continuous billing typewriting machine, the combination with a traveling 75 carriage having a rearward extension, of a carbon-paper carriage mounted upon said extension, clamping means carried by said carbon-paper carriage for gripping plies of work-sheets therebetween at the extreme 80 rear of the carbon-paper carriage, said means comprising lower jaws fixed to said carbon-paper carriage, one at each side thereof, and upper jaws pivotally mounted independently of each other for co-operation with said lower jaws, means for swinging each of said upper jaws independently of the other to effective position against the respective lower jaw to grip the work-sheets, and means common to the swinging 90 jaws for swinging both jaws away from effective positions.

2. In a continuous billing typewriting machine, the combination with a traveling carriage having a rearward extension, of a 95 carbon-paper carriage mounted upon said extension, clamping means carried by said carbon-paper carriage for gripping plies of work-sheets therebetween, said means comprising lower jaws fixed to said carbon-paper carriage, one at each side thereof, and upper jaws pivotally mounted for co-operation with said lower jaws, said upper jaws being independent of each other, means for 100 swinging each of said upper jaws to effective position against the respective lower jaw to grip the work-sheets, and means for engaging said upper jaws to lock them in effective positions, said last-named means being operable to release said upper jaws 110 and to swing both of said upper jaws simultaneously away from said lower jaws to ineffective position.

3. In a continuous billing typewriting machine, the combination with a traveling 115 carriage having a rearward extension, of a carbon-paper carriage mounted upon said extension, clamping means carried by said carbon-paper carriage for gripping plies of work-sheets therebetween, said means comprising lower jaws fixed to said carbon-paper carriage, one at each side thereof, and upper jaws pivotally mounted for co-operation with said lower jaws, said upper jaws being independent of each other, means for 120 swinging each of said upper jaws to effective position against the respective lower jaw to grip the work-sheets, means for simultaneously swinging said upper jaws to 125 ineffective position away from said lower 130

jaws to release the work-sheets, said last-named means comprising a rock-shaft journaled in said carbon-paper carriage, rock-arms fixed to said shaft, and members carried by said rock-arms for engaging said upper jaws to raise the upper jaws when said rock-shaft is operated, and means for operating said rock-shaft comprising a forwardly and rearwardly movable handle, and

a rock-arm pivotally connected at one end to said handle and fixed at the other end to said shaft, said members being effective to raise the upper jaws when the handle is operated forwardly. ¹⁰
